BY *Samuel Herrick*,
ATTORNEY.

UNITED STATES PATENT OFFICE

WILLIAM R. FARREN, OF TAMAQUA, PENNSYLVANIA, ASSIGNOR TO ATLAS POWDER COMPANY, OF WILMINGTON, DELAWARE, A CORPORATION OF DELAWARE

EXPLOSIVE ASSEMBLY

Application filed November 5, 1930. Serial No. 493,610.

This invention relates to certain new and useful improvements in explosive assemblies. It has for its object, the provision of a rigid waterproof blasting cartridge, the shell or envelope being of non-sparking materials, and so constructed as to eliminate any possibility of rupturing or tearing during handling and loading into bore holes, and in addition to have a high degree of water resistance.

10 In this latter respect it is believed to be superior to any blasting cartridge shell used heretofore in the explosive industry, with the one exception of the waterproofed fabric type outlined in the pending patent applications 15 of R. L. Hill, Serial Number 436,888 filed March 18, 1930, now Patent No. 1,824,141, and Serial Number 439,077, filed March 26, 1930.

It is a well known fact that in a large percentage of blasting operations water is present in varying amounts. The presence of water is in most cases objectionable since it necessitates special preparation of the bore holes and modification of blasting procedure, or the selection of a highly water resistant explosive. Eliminating the water from bore holes is a costly and troublesome procedure and is oftentimes of little avail, since in the majority of cases, the holes fill up again quite quickly. In such instances, where an explosive, possessing mediocre or poor water resistance, is used, it is obviously necessary to load and fire the holes within a short period of time, or the efficiency of the explosive will be seriously affected. This procedure not only 35 reduces the speed and efficiency of loading, but also impairs the blasting efficiency of the explosive, since the results obtained in shooting several holes at one time are superior to those obtained when shooting the same number, one or two at a time.

The use of explosives that inherently have sufficient water resistance to withstand contact with water for appreciable periods of time and thus do not require protective envelopes, is in many instances objectionable. These types of explosives are usually comparatively expensive. They are in addition, invariably very dense and almost without exception, have high velocity of detonation,

and thus contribute a localized shattering effect which is not always desirable.

My invention, hereinafter set forth, provides a waterproof cartridge shell of such efficiency that the selection of explosives for wet blasting conditions may be based alone on their explosive properties and costs; their water resistance being eliminated entirely from consideration. For example, a certain wet stripping operation may require the slow, 60 heaving action of a low explosive, such as black blasting powder, to provide the most desirable effectiveness and cost. Heretofore, a more expensive, highly water resistant gelatin dynamite would have to be substituted, 65 with poorer effectiveness resulting. With my invention, the proper type of non-water resistant explosive may be used, even under the most severely wet conditions.

Without restricting the invention thereto, I 70 describe the same with reference to the embodiment thereof illustrated in the accompanying drawings.

Figure 1 is a perspective view of one end of a cartridge constructed in accordance with 75 the invention.

Figure 2 is a vertical sectional view illustrating one embodiment of the invention.

Figure 3 is a vertical sectional view illustrating another embodiment of the invention. 80

Usually both ends of the cartridge will be alike, although the invention is not limited in this respect. The explosive assembly of the present invention differs from the commonly used explosive assemblies in that it embraces the idea of utilizing a preformed carton-like receptacle of such stiffness and rigidity as to stand up of its own strength.

In the drawings, 5 designates a cylindrical carton-like body adapted to receive explosive material in any suitable form, indicated at 6. A reinforcing cap 7 is adapted to fit down upon the cylindrical body 5 in such manner that its outer face will lie flush with the outer face of the body 5. 8 designates a cap of 90 flexible waterproof material such as rubber cloth or otherwise. A ring or band 9 is adapted to slide down over the cap 7 and body 5 and bind the lower portion of the flexible cap 8 in place. In the form of the invention 95 100

illustrated in Figure 3, the cylindrical carton-like body 5^a receives the explosive material 6^a and any suitable form of plug 7^a is disposed outwardly of the explosive material and constitutes the reinforcing element for the flexible waterproof cap or sheet 8^a which is bound in place by a ring or band 9^a in the manner previously described. It is common practice in the paper manufacturing industry to make relatively stiff paper cartons in many different ways and of many different materials. Sometimes they are made of a single thickness of material and other times they are made in laminated form with the various plies cemented together. I contemplate the use of any of the known methods of manufacturing the cartons or receptacles 5, 5^a. Where these cartons comprise a plurality of plies of material, I contemplate a use of suitable asphaltic or other waterproofing compositions to insure that the completed structure will be wholly waterproof throughout its length. I contemplate the use of solid manila paperboard, straw-chip paperboard or any other suitable non-sparking material, in this relation. It should be clearly understood, however, that any one or combination of more than one non-sparking materials may be used and that they may be held together and waterproofed by any suitable material or materials, without being outside the scope of my invention, as long as the resulting cylindrical wall body is sufficiently sturdy and waterproof for use with my novel assembly. Examples of suitable non-sparking materials are cardboard, heavy paper, fiber, pressed pulp, straw chip board, solid manila paperboard, sheet aluminum, etc., whereas examples of suitable adhesive and waterproofing materials are paraffin wax, mineral tar, animal pitch, waterproof glue, nitrocellulose cement, etc.

The reinforcement cap is preferably of a cheap, non-sparking material such as paperboard, which is capable of being pressed into the desired shape and has the desired strength, although any other suitable material may be used, for this purpose, without being outside the scope of my invention. Further, the means of reinforcing the flexible waterproof cap may take other forms, as for example: rigid flanged plugs, rigid unflanged plugs (held in place either by the contents of the shell as in Figure 3 or by tacks), rigid explosive contents such as pelleted black powder, and the like.

For the waterproof cap I prefer to use a circular piece of flexible rubberized cloth. However, any material or shape of cap that will furnish the required waterproofing, such as treated or untreated fabric, various types of paper, sheet rubber, rubber caps, etc., may be used without being outside the scope of my invention. I have found, by experiment, that rigid waterproof caps are less desirable

for my purpose than non-rigid or "flexible" waterproof caps, because they are more difficult to seal on to the cylindrical wall body in a waterproof manner, besides having a greater tendency to crack open and leak under water pressure than a reinforced, non-rigid waterproof cap.

The most desirable type of annular retaining band is of construction similar to that of the cylindrical wall body. It should be clearly understood, however, that any type of band that will produce the desired tension and retaining effect, such as those constructed of adhesive tape, friction tape, rubber tape, rubber bands, insulated non-sparking wire, etc., are within the scope of my invention.

The cap 7 is formed to fit over the end of the cylinder very snugly and is applied before the waterproofed fabric; it being cemented in place with molten asphalt or other cementing material, which will insure the desired degree of waterproofing. In addition to contributing towards the water resistance of the assembly the cap furnishes the required physical strength to the ends of the container.

The waterproof fabric is also applied with the aid of a cementing material, and, as noted before, is held in position by the retaining band 9. This band is originally constructed so as to slide freely over the cap and cylinder but due to the introduction of the cementing material, contributes an appreciable binding effect to the completed assembly.

The total assembly, loaded with the explosive, may be dipped in paraffin to contribute still further water resistance, and may be equipped with any known form of cartridge lowering attachment such for example as that disclosed in the pending patent application of W. R. Farren, Serial Number 483,930, filed September 23, 1930.

Having described my invention, what I claim is:

1. A blasting cartridge shell of the character described, comprising a non-sparking, rigid and waterproof wall body, a flexible cap of rubberized fabric cemented in place over each end with molten asphalt, a non-sparking reinforcement plug for each end and non-sparking annular retention bands to hold said caps on each end of the cylindrical wall body.

2. A blasting cartridge shell of the character described, comprising a non-sparking, rigid and waterproof wall body; a flexible, waterproof cap for each end, a snug fitting formed fiber reinforcement cap cemented in place over each end with molten asphalt and annular retention bands of non-sparking material to hold said caps on each end of the cylindrical wall body.

3. A blasting cartridge shell of the character described, comprising a rigid, waterproof body of laminated paperboard construction, the plies of which are cemented to-

gether with molten asphaltic compounds; waterproof caps of rubberized fabric, cemented in place on each end with molten asphaltic compounds; a snug-fitting reinforcement cap for each end and non-sparking annular retention bands to hold said waterproof caps on each end of the cylindrical wall body.

4. A blasting cartridge shell of the character described comprising a rigid, waterproof body of laminated paperboard construction, the two or more plies being cemented together with molten asphaltic compounds, waterproof caps of rubberized fabric cemented in place over each end with molten asphaltic compounds, a snug-fitting reinforcement cap of formed fiber cemented over each end with molten asphaltic compounds and annular retention bands to hold said waterproof fabric caps on each end of the cylindrical wall body and in completely enclosing relation to the reinforcement caps.

5. A blasting cartridge shell of the character described, comprising a non-sparking, laminated, cylindrical wall body having two or more plies cemented together with a waterproof compound; a snug-fitting reinforcement cap or plug for each end, a flexible, waterproof cap fitted over said reinforcement plug or cap at each end; and a non-sparking, annular band retaining said waterproof cap at each end.

6. In an explosive assembly, a carton-like cylindrical body adapted to receive explosive material, a reinforcing element closing the end thereof, a sheet of snug-fitting flexible waterproof material disposed over said reinforcing element, and an annular binding member of non-sparking material binding said sheet of flexible material about said body, said binding material being disposed a material distance inwardly of said reinforcing element.

7. In an explosive assembly, a carton-like cylindrical body adapted to receive explosive material, a reinforcing element closing the end thereof, a sheet of flexible waterproof material cemented over said reinforcing element and about said body and an annular binding member of non-sparking material binding said sheet of flexible material about said body, said annular binding member being of such diameter as to adapt it to slide down over said cylindrical body to a point below said reinforcing element, and to forcibly press the inner portion of the cemented waterproof sheet into engagement with the wall of said cylindrical body.

8. An explosive assembly comprising a rigid self-supporting paper cylindrical body, a reinforcing cap for closing the upper end thereof, a sheet of flexible waterproof material fitted over said cap and extending materially therebelow, said cap being cemented upon said body with a waterproofing com-

position and said flexible material being cemented upon the cap and body by a waterproofing composition, and a sliding band of non-sparking material adapted to slide down over the flexible material, cylindrical body 70 and cap to bind said flexible material in place as described.

9. An explosive assembly comprising a rigid supporting paper cylindrical body, a reinforcing cap closing the end thereof and 75 so associated with the cylindrical body as to leave the exterior surface of the assembly of uniform diameter throughout its length, a cap of snugly fitting waterproof fabric fitted over the end of the container and extending 80 a material distance inwardly of the reinforcing closure cap, said cap of waterproof material being cemented in place by waterproof material, and a band of non-sparking material slidably fitted over said cap of flexible 85 waterproof material and of such internal diameter as to constrict the waterproof fabric against the cemented surface of the body portion, inwardly of the reinforcing cap.

10. A blasting cartridge of the character described comprising a body of explosive material, a shell comprising a non-sparking rigid and waterproof cylindrical wall body, an imperforate non-sparking waterproof cap cemented in place upon said body with a waterproof composition, a flexible cap formed of a waterproof sheet cemented snugly over the first named cap, and an annular retention band holding the last named cap in place upon the said cylindrical wall body, said 100 retention band being of non-sparking material.

In testimony whereof he affixes his signature.
